E. A. FREED

FURNACE JOINT

Filed Nov. 22, 1923

INVENTOR.

Edward A. Freed

UNITED STATES PATENT OFFICE.

EDWARD A. FREED, OF MOLINE, ILLINOIS.

FURNACE JOINTS.

Application filed November 22, 1923. Serial No. 678,487.

To all whom it may concern:

Be it known that EDWARD A. FREED, a citizen of the United States, residing at Moline, in the county of Rock Island and State of Illinois, has invented certain new and useful Improvements in Furnace Joints, of which the following is a specification.

My invention relates to improvements in furnace joints for hot air furnaces and similar structures.

The objects of my invention are:

1. To provide means which will allow for expansion and contraction of the different sections of a furnace without injury to the joints thereof.

2. To provide means which will automatically seal the joints of a furnace against leakage due to contraction and expansion or loosening of the joint from other cause.

20 3. To provide a furnace joint which will expand and contract without injuring or loosening the cement filling therein.

I attain these objects by the mechanism illustrated in the accompanying drawing, 25 in which is shown a perspective view in section of a portion of a furnace wall containing my joint and portions of an upper and lower section of a furnace, 1 and 2, respectively secured together by a layer of cement, 3.

In constructing my joint, I carefully smooth off by grinding or otherwise one of the surfaces to be joined, preferably the lower surface 1^a of the upper section. I leave the upper surface 2^a of the other section in its natural rough state as cast. Then I place a layer or coating of cement upon the roughened surface, spreading it carefully and evenly and pressing it thereon 35 with considerable force so as to make the cement enter all the irregularities in the surface. I then mount the smooth edge of the upper section upon the cemented edge of the adjacent section.

40 45 Adjacent the upper edge of the lower section, I provide a channel or trough, 6, which is formed by a projecting bead or rim, 5, secured to or formed integral with the section, 2. After the upper section has been seated upon the lower one as shown, I fill this trough or channel, 6, with a fine sand, 4, or other suitable material. The material used for filling the channel, 6, should be a material which will not cake and which is sufficiently fine grained to prevent the escape of gases through it.

After a furnace is set up with the joints formed as stated, the greater adherence of the cement to the roughened surface of one of the sections will cause it to adhere more strongly to that surface than it will adhere to the smoothly ground surface of the adjacent section. The result will be that in case the two adjacent sections expand or contract unevenly, the cement will adhere to the roughened surface and break away from or slide upon the smoothed surface. The smoothed surface will not tear or break up the cement as a roughened surface would do, but will tend to allow the cement to slide inwardly or outwardly upon it with very little injury.

In case of uneven expansion of the adjacent sections, the yielding nature of the sand, 4, in the channel, 6, will allow it to bulge upwardly and whenever the sections resume their normal relative position by contraction, the force of gravity will cause the sand to resume its normal position in the channel or trough, 6.

If desired, a light coating of graphite, pulverized mica or other suitable material, may be sprinkled in the channel, 6, before the sand is placed therein and likewise, a very light coating of graphite, pulverized mica or other suitable material, may be applied to the smooth lower surface of the upper section, if desired, before being seated upon the cemented upper surface of the lower section, to act in the nature of a lubricant and assist in permitting the relative movement due to contraction to take place without breaking up or injuring the cement filler.

Having described my invention, I claim:

1. In a furnace joint, the combination with a section having a rough face, of a section mounted adjacent thereto having a smooth face and a filler inserted between the rough and smooth faces and secured to the rough face.

2. In a furnace joint, the combination with a section having a rough face, of a section mounted adjacent thereto having a smooth face and a filler inserted between the rough and smooth faces and secured to the rough face, and a trough united with the lower section surrounding the furnace adjacent the joint and filled with non-combustible granular matter.

3. In a furnace joint, the combination with a section having a rough face, of a sec-

- tion mounted adjacent thereto having a joint and filled with a non-combustible, granular material.
4. A furnace joint comprising a section having a rough face and a section having a smooth face mounted adjacent thereto and a filler inserted between the rough and smooth faces and secured to the rough face, and a trough, united with the lower section, surrounding the furnace adjacent the joint and filled with sand.
5. A furnace joint comprising adjacent sections mounted with a filler of cement between adjacent edges thereof and a trough united to the lower section surrounding the joint and filled with sand.
6. A furnace joint comprising adjacent sections mounted with a filler of cement between adjacent edges thereof and a trough united to the lower section surrounding the joint and filled with sand.
7. A furnace joint comprising a lower section with an upper section seated thereon, with a filler of cement between them and a trough united to the lower section surrounding the joint and filled with sand, and means for allowing expansion and contraction without disturbing the cement filler.
8. A furnace joint comprising a lower section with an upper section seated thereon, with a filler of cement between them and a trough united to the lower section surrounding the joint and filled with a non-combustible, granular material, and means for allowing expansion and contraction without disturbing the cement filler.

In testimony whereof he affixes his signature.

EDWARD A. FREED.
